UNITED STATES PATENT OFFICE.

DANIEL F. JONES, OF CHICAGO, ILLINOIS.

SIGNAL FLAG AND METHOD OF MAINTAINING SAME.

Application filed November 5, 1926. Serial No. 146,296.

This invention relates generally to improvements in signal flags and methods of maintaining same and relates more particularly to flags of the type used in railroad service.

Signal flags such as now extensively used in railroad service comprise a staff and a flag cloth or bunting nailed at one end thereto. This bunting is only of the area of the flag to be displayed, which is usually about 16 inches square. This is the size which it has been found is necessary to attract attention when the train is moving at usual speed. Due to the speed of the train, the force of the wind, etc., a constant whipping and flapping occurs. The result is that it quickly frays at the free end thereof and rapidly wears down. After the length of the flag is reduced by such wear, to that dimension where its use for its intended purpose must be discontinued, it is discarded as waste and a new flag substituted in its place. Such flags when the length of service they yield is considered, are expensive. The flag is usually discarded when it has been reduced to half its normal size, the remaining half being a total loss.

The purpose of these signal flags is to inform railroad officials and others whether the train is a special, a section of some train, etc. This is an important function and upon it may hinge the safety of the train. To operate at highest efficiency the signal flag should never be greatly smaller than its initial size. Yet it is the practice to use them until they have been reduced to about half size. Hence for a great part of the time such signal flags, as heretofore constructed do not fully serve their intended purpose.

The primary object of the invention is to provide a signal flag of this kind, wherein an excess or supply of bunting is so associated with the staff that such excess or supply may be drawn on from time to time as the flag wears down to replace the worn down portion which is cut off and thus restore or maintain the flag to be displayed to full flag size.

A further object of the invention is to provide a novel bunting for the flag, in the form of a strip greatly in excess of a single flag length, with top and bottom selvage margins and with transverse bands of more closely woven portions than the body portions of the bunting between said bands which are similar to selvage weave, whereby the bunting may be cut off along such bands to form new selvage ends, and at the same time provide contrasting tone stripes which render the flag more visible and more quickly attracts attention thereto.

Still another object of the invention is to provide a flag of the kind wherein the excess or supply of bunting is wrapped or rolled upon one end of the staff and is enclosed and protected by a detachable casing, which may be removed so that the desired amount of bunting may be withdrawn or unwound from the bunting excess or supply after which the casing is again applied to the staff.

These objects of the invention as well as others, together with the many advantages thereof, will more fully appear as I proceed with my specification.

In the drawings:

Fig. 1 is a view partly in elevation and partly in section of a signal flag embodying therein the preferred form of my invention.

Fig. 2 is a view in elevation of the signal flag on a smaller scale as viewed from the bunting slot side thereof.

Fig. 3 is a transverse horizontal sectional view as taken on the line 3—3 of Fig. 1.

Fig. 4 is a view in elevation on an enlarged scale of a fragment of flag bunting and which will be more specifically referred to later.

Fig. 5 is a fragmentary perspective view showing a modified form of reinforcing the flag along transverse stripes or zones.

Referring now in detail to that embodiment of the invention illustrated in the accompanying drawing:—1 indicates as a whole the staff of the flag and 2 indicates the flag cloth or bunting of the flag. The staff is cylindrical in cross section and may be made of any suitable material, preferably of wood and said staff is usually tapered at its bottom end as at 3 to snugly fit in a holding socket. The flag cloth or bunting is in the form of an elongated strip or web of a width equalling the height of the flag and of a length greatly in excess of a single flag length. The top end of the staff is split longitudinally as at 4, (see Fig. 3), and one end of the bunting is placed within said split and secured therein in any suitable manner. The bunting is then rolled or wound upon the top end of the staff as shown at 5 in Figs. 1 and 3, thus providing thereon the excess bunting forming the supply which is

drawn upon from time to time to maintain the flag to be displayed to the proper length as shown in Fig. 1. To prevent the bunting rolled on the staff from telescoping thereon 5 I provide a flange collar 6 on the staff to support the bottom end of the rolled on bunting.

The bunting rolled on the staff is enclosed in a tubular metallic casing 7 of proper diameter and said casing snugly fits in a ferrule 8 having a substantially tight friction fit upon the staff. The top end of said casing is closed by a wall 9 as shown. In one side of the casing is a longitudinally extending flanged slot 10 that extends from a point near its top end downwardly to open through the bottom end, which bottom end of the casing as before described snugly fits in but is detachable from the ferrule 8. An 15 amount of flag cloth or bunting is unwound from the staff and extends through the casing slot 10 to provide the desired length of flag to be displayed.

The flag cloth or bunting employed here- 20 in is of a novel arrangement. It is of substantially open weave and has top and bottom selvages or margins 2^a and 2^b and transversely extending bands of selvage woven portions 2^c, which are spaced longitudinally 25 the desired distance apart. The fields or portions 2^d between said bands being of comparatively coarse or open weave, I prefer to make the displayed portion of my improved signal flag about eighteen inches square and 30 35 I find it desirable to space said bands about three inches apart so that to maintain the flag to the correct size, six of such fields must be exposed, the free end of the flag being defined by one of said selvage bands 2^c. It is to be understood that these dimensions are merely illustrative.

When such a flag is in use it flaps in the wind and after continued use its end as defined by the outermost field or open weave portion 2^d becomes frayed and ragged. Instead of discarding the entire flag, said outermost field or open weave portion is cut off along the outer edge of the next selvage band portion and the casing 7 is removed 40 from the staff and an amount of bunting equal to that cut off is removed from the excess or supply on the staff to make the flag full length again after which the casing is applied and the flag is once more complete. 45 This compensates for the worn out parts of the flag and this renewing may be repeated until the excess or rolled on supply is exhausted. Thus the life of a flag embodying 50 my invention is greatly extended compared to that of a standard signal flag as now used. The flapping of the flag in the wind cannot 55 act to draw out from the casing any amount of bunting because this is prevented by the tight fit of the staff in the socket, which 60 cannot turn therein.

The bunting made as described has another advantage the selvage like band portions being of a closer or more dense weave than the field portions between said bands, imparts a transverse relative stiffness to the 70 bunting so that the said fields may be of a coarser and more open weave than was heretofore possible. Thus the wind or moving air can more freely pass through the flag so that the flapping is reduced and less textile material may be employed in the bunting without making it too flimsy. Another feature is that the selvage bands not only reinforce the bunting as described but they 75 impart a different color tone but not color 80 to the flag as a whole which is advantageous because it provides that contrast which makes the flag more visible and thus it more readily attracts the attention of the observer thereto.

In the form of my invention previously described the transverse reinforcing band portions are formed by associating certain of the threads of the fabric closer together than the body of the fabric. I may however secure the desired reinforcing effect by providing a fabric of the usual form and folding portions thereof backwardly upon adjacent portions as indicated at 15 in Fig. 5. These folded portions are preferably stitched by means of a double line of stitching as indicated at 16. In this construction as in the other the longitudinal edges are preferably provided with selvage 95 bands 2^a.

My improved flag has many advantages; its period of usefulness is greatly increased and it eliminates the necessary and frequent replacement of flag as is now the custom. The bunting being reinforced as described 100 makes it strong and durable and at the same time eliminates the necessity of the substantially close weave and hemming along the top and bottom margins now necessary in standard signal flags as now used.

While in describing my invention, I have referred to many details of construction as well as form and arrangement of the parts thereof, I do not wish to be limited thereto except as may be pointed out in the appended 110 claims.

I claim as my invention:

1. A signal flag embodying therein a strip of bunting in excess of a flag length, one end of said bunting being disposed upon itself to form a supply and the other end forming the flag proper and means for holding said supply and from which may be withdrawn an amount of bunting sufficient to maintain the flag proper at its desired 120 length.

2. A signal flag embodying therein, a staff, a strip of bunting in excess of a flag length, one end of said bunting strip being rolled upon said staff to form a supply and 130

the other end forming the flag proper which is maintained at proper size by withdrawal of the bunting from the supply on the staff.

3. A signal flag embodying therein, a staff, a strip of bunting in excess of a flag length, one end of said bunting strip being rolled upon said staff to form a supply and the other end forming the flag proper which is maintained at proper size by withdrawal 10 of the bunting from the supply on the staff and means on the staff preventing telescoping of the supply on the staff.

4. A signal flag embodying therein, a staff, a strip of bunting in excess of a flag

length, one end of said bunting strip being 15 rolled upon said staff to form a supply and the other end forming the flag proper which is maintained at proper size by withdrawal of the bunting from the supply on the staff and a collar on the staff below said supply 20 and engaged thereby to prevent telescoping of the same and a casing removably mounted on the staff and enclosing said supply and having a longitudinal slot through which said other end of the bunting extends. 25

In testimony whereof, I have hereunto set my hand, this first day of November, 1926.

DANIEL F. JONES.
